SOUND TRANSMITTING DEVICE

David F. Burke, Manchester-by-the-Sea, Mass.

Application October 27, 1930. Serial No. 491,368

17 Claims. (Cl. 274—37)

This invention relates to an improvement in sound transmitting devices and has for its object to provide a device by means of which sound vibrations, particularly those from high-frequency tones, may be transmitted with a minimum amount of distortion so that they may be reproduced without changing their natural quality.

Another object of the invention is to embody in the structure of the device a means for increasing the intensity of the vibrations without distorting the same.

Still another object of the invention is to provide a means for dampening or checking the after vibrations with the result that a more faithful reproduction is obtained, both instrumental music and the human voice being reproduced with equal clarity and without the usual distortion.

The invention consists in a sound transmitting device as set forth in the following specification and particularly as pointed out in the claims thereof.

Referring to the drawing:

Fig. 1 represents an enlarged side elevation of a sound transmitting device embodying my invention.

Fig. 2 is an enlarged plan view of the device.

Fig. 3 is an enlarged central longitudinal section through the device.

Like numerals refer to like parts throughout the several views of the drawing.

In the drawing, 5 represents a casing preferably constructed of hard vulcanized rubber or other material having similar properties and characteristics. The casing 5 embodies therein a body member 6 and a closure member 7 which is separable from the member 6 at 8 in order that access may be had to a chamber 9 which is formed within the member 6.

40 A sound conducting member in the form of a needle or stylus 10 is located within an opening 11 provided therefor in the casing member 6, being rigidly secured therein by means of a screw 12. The stylus 10 is reduced in diameter at 13 and the reduced portion projects a short distance into the chamber 9.

Rigidly mounted in the casing member 7 is a sound conducting member 14, the upper portion of which projects a predetermined distance 50 above the upper extremity of the casing member 7 and terminates in a tapered point 15. The sound conducting member 14 is preferably constructed of the same material as is the stylus 10 and is of the same diameter as is the main 55 portion of said stylus. In effect, the sound conducting members 10 and 14 comprise two spaced-apart members of a needle or stylus, the member 14 being provided for the purpose of receiving and transmitting the sound vibrations and 60 also for securing the device of this invention in

a sound reproducing device in exactly the same manner as is the ordinary phonograph needle or stylus.

Located at the bottom of the chamber 9 are a plurality of superposed layers of a thin resilient material, preferably thin rubber discs 16, the lowermost disc of which contacts with the upper extremity of the stylus 10. The discs 16 are held seated at the bottom of the chamber 9 by means of a ring 17 which, in turn, is held in position 65 by being cemented to the wall of the chamber 9. The peripheral portion, furthermore, of the discs 16 may be cemented to the wall of the chamber 9 if it is so desired. Located in the space between the bottom surface of the chamber 9 and the under side of the lower disc 16 are a plurality of metallic members 18 preferably in the form of steel balls, and these members act to stretch the central portion of the discs 11 upwardly, and portions of certain of said discs contact with the periphery of the reduced portion 70 of the stylus 10. It is desirable that the metallic members 18 shall be smeared and the spaces therebetween filled with a suitable lubricant such, for example, as vaseline.

Attached to the lower surface of the casing member 7, by means of suitable cement, is a ring 19, and cemented to the under surface of the ring 19 is a thin rubber disc 20. Another ring 21 is cemented to the under surface of the disc 20 and a disc 22 is cemented to the under surface of the ring 21. The diameter of the rings 19 and 21 and discs 20 and 22 are preferably the same as the diameter of the chamber 9, so that when these parts are all assembled, the peripheries of the rings and discs will contact with the wall of said chamber.

In transmitting sounds through the device of this invention the vibrations in passing from the sound conducting member 10 through the casing 5 to the member 14, will be so influenced by the presence of the plurality of rubber discs 16, the lowermost of which contacts with the upper extremity of the stylus 10, and by the presence of the rings 19 and 21 and discs 20 and 22, which are secured to the upper casing member 7, that the usual after vibrations will be damped or checked, with the result that a more faithful reproduction of all the tones transmitted will be obtained. At the same time the presence of the small metallic members 18 within the space surrounding the reduced portion of the stylus 10 will increase the intensity of the vibrations for most of the frequencies occurring in speech and 100 music without causing them to be distorted. By providing the tapered point upon the upper portion of the sound conducting member 14 a faster 105 vibration of the upper end of this member is obtained.

I claim:

1. A sound transmitting device having, in combination, a casing provided with a chamber therein, a stylus in two parts mounted in said casing, and tympanic membranous members within said chamber and engaging the wall thereof.
2. A sound transmitting device having, in combination, a casing provided with a chamber therein, a stylus in two parts mounted in said casing, and a plurality of tympanic membranous members spaced apart within said chamber and engaging the wall thereof.
3. A sound transmitting device having, in combination, a casing provided with a chamber therein, a stylus in two parts mounted in said casing, and a plurality of tympanic membranous members mounted within said chamber and provided with spaces therebetween.
4. A sound transmitting device having, in combination, a casing provided with a chamber therein, a stylus in two parts mounted in said casing, and a tympanic membranous disc within said chamber between the parts of said stylus.
5. A sound transmitting device having, in combination, a casing provided with a chamber therein, a stylus in two parts mounted in said casing, and a tympanic membranous disc within said chamber between the parts of said stylus and engaging the wall of said chamber.
6. A sound transmitting device having, in combination, a casing provided with a chamber therein, a stylus in two parts mounted in said casing, and a plurality of tympanic membranous discs spaced apart within said chamber and engaging the wall thereof.
7. A sound transmitting device having, in combination, a casing provided with a chamber therein, a stylus in two parts mounted in said casing, and a tympanic membranous member within said chamber and contacting with the inner extremity of one of the parts of said stylus.
8. A sound transmitting device having, in combination, a casing provided with a chamber therein, a stylus in two parts mounted in said casing, and a tympanic membranous disc within said chamber contacting with the inner extremity of one of the parts of said stylus and also with the wall of said chamber.
9. A sound transmitting device having, in combination, a casing provided with a chamber therein, sound conducting members mounted in said casing, one of said sound conducting members projecting into said chamber, a resilient member within said chamber and contacting with the inner extremity of said last-mentioned sound-conducting member and also with the wall of the chamber, and a mass of small metallic members located within said space surrounding the inner extremity of said last-named sound conducting member.
10. A sound transmitting device having, in combination, a casing provided with a chamber therein, a stylus mounted in said casing and comprising two parts, spaced apart within said chamber, and a tympanic membranous member within said chamber between the extremities of the parts of said stylus and contacting with the wall of the chamber.
11. A sound transmitting device having, in combination, a casing provided with a chamber therein, a stylus mounted in said casing and comprising two parts spaced apart within said chamber, and a plurality of tympanic membranous discs within said chamber contacting with the wall thereof, one of the discs also contacting with the inner extremity of said stylus that projects into the chamber.
12. A sound transmitting device having, in combination, a casing provided with a chamber therein, a stylus mounted in said casing and comprising two parts spaced apart, one of said parts projecting into said chamber, and a plurality of tympanic membranous discs spaced apart within said chamber, one of said discs contacting with the inner extremity of the part of the stylus which projects into the chamber.
13. A sound transmitting device having, in combination, a casing provided with a chamber therein, a stylus mounted in said casing and comprising two parts spaced apart, one of said parts projecting into said chamber, and a tympanic membranous disc within the chamber and engaging the wall thereof, said disc also contacting with the extremity of the stylus.
14. A sound transmitting device having, in combination, a casing provided with a chamber therein, a stylus mounted in said casing and comprising two parts spaced apart, one of said parts having a reduced portion projecting into said chamber, a resilient disc within the chamber and engaging the wall thereof, said disc also contacting with the extremity of the stylus, and a mass of small metallic members located within the space surrounding the reduced portion of the stylus.
15. A sound transmitting device having, in combination, a casing provided with a chamber therein, a stylus mounted in said casing and comprising two parts, one of said parts projecting into said chamber and the other of said parts terminating at its outer extremity in a point and being adapted to be attached to a sound reproducing device, and a tympanic membranous disc within said chamber contacting with the extremity of said stylus that projects into said chamber and also with the wall of the chamber.
16. A sound transmitting device having, in combination, a casing provided with a chamber therein, a stylus mounted in said casing and comprising two parts, one of said parts projecting into said chamber and the other of said parts terminating at its outer extremity in a point and being adapted to be attached to a sound reproducing device, a plurality of resilient discs within said chamber, one of said discs contacting with the extremity of said stylus that projects into the chamber and also with the wall of the chamber, and a mass of spherical metallic members located beneath said last-named disc and surrounding the portion of the stylus which contacts with said disc.
17. A sound transmitting device having, in combination, a casing provided with a chamber therein, a stylus mounted in said casing and comprising two parts, one of said parts projecting into said chamber and both of the parts projecting outwardly from opposite sides of the casing, and a plurality of tympanic membranous discs within said chamber contacting with the wall thereof, one of the discs also contacting with the inner extremity of said stylus that projects into the chamber.

DAVID F. BURKE.
